HERMETICALLY SEALED PUMP

BACKGROUND OF THE INVENTION

1. Field of the Invention

This invention relates to a hermetically sealed pump in which fluid is moved from one location to another by means of a pump being driven by a pair of permanent magnetic discs. The permanent magnetic disc connected to the displacement pump is driven by another permanent magnetic disc connected to the shaft of a motor. The magnetic discs are separated by a nonmagnetic and nonconducting element.

2. Description of the Prior Art

It is known to move or pump liquid in a system that requires the system to be hermetically sealed from external environment. However, the apparatus and methods used heretofore have proved to be of low efficiency compared with applicants' device which pumps liquids at a high efficiency, in a safe manner, and in a hermetically sealed environment.

SUMMARY OF THE INVENTION

According to the present invention, the pump is hermetically sealed against the external environment. The movement of the fluid is caused by two permanent magnetic discs, separated by a nonmagnetic and nonconducting seal; one magnetic disc being driven by a motor. The driven magnetic disc transmits rotary motion through the nonmagnetic seal to the other magnetic disc. The second driven magnetic disc is connected to a pump means which pumps the fluid through the unit.

BRIEF DESCRIPTION OF THE DRAWINGS

FIG. 1 shows an elevational view of the pump assembly unit connected to a motor;

FIG. 2 shows an end view of the pump unit with parts being broken away, to show the inlet and outlet parts of the pump;

FIG. 3 shows a cross-sectional view of the pump showing the novel drive means;

FIG. 4 shows a magnetic disc of the type used in the drive means;

FIG. 5 shows an elevational view of the pump housing; and

FIG. 6 shows a perspective view of the piston drive oscillating ring.

DESCRIPTION OF THE INVENTION

The hermetically sealed pump, generally indicated at 10, shown in FIG. 1, is connected to the mounting adapter 13 of motor unit 12 by means of threaded bolts 15. Fluid is adapted to enter pump 10 by means of pump inlet line 17 and exit through line 19.

Referring more specifically to FIG. 3, the shaft 21 of motor 12 is threaded connected to an adapter 23. The adapter 23 is held thereto by means of a threaded set screw 25. The motor driven magnetic disc 27 is connected to the adapter 23 and attached to the reinforcing ring 29 by epoxy or other suitable means. This comprises the motor or driving side of the unit.

The pump or driven side of the unit comprises a pump shaft housing 31 mounted between the motor mounting adapter 13 and the pump block 33. Seals 35 and 37 are interposed between each mounted housing and pump block to prevent leakage of fluid to the atmosphere. The pump shaft housing 31 is comprised of a recessed chamber 39 and an axial bore 41. Within the bore 41 is a carbon, ceramic bushing or other suitable material 43 which provides rotational stability of eccentric shaft 47. The eccentric shaft adapter 45 is secured to the threaded end 51 of shaft 47 by means of a threaded set screw 53. A magnetic disc 57 is connected to the adapter 45 and attached to the reinforcing ring 55 by epoxy or other suitable means. A nonmagnetic and nonconducting seal 59 is interposed between the two magnetic discs 27 and 57 respectively for purposes to be hereinafter disclosed.

As shown in FIG. 4, the magnetic disc is of a permanent magnetic type with multiple poles about the respective face

thereof. The laws of magnetism clearly define that similar polarity will repel each other and unlike polarity will attract each other; thus the polarity on opposing faces of a pair of magnetic discs, such as disclosed herein, will repel and attract each other in continuous and simultaneous fashion. It has been found that for purposes disclosed herein, a magnetic disc with four or more magnetic poles performs with the efficiency desired.

10 In the operation, as the magnetic disc 27 is rotated by means of motor 12, the other magnetic disc 57 is caused to rotate by means of the magnetic coupling between the two opposing faces of the magnetic discs. The seal 59, being of nonmagnetic quality allows the transfer of the rotating magnetic field, thereby causing substantially equal rotation of the driven magnetic disc 57. It is to be noted that when the maximum torque of a synchronous drive, such as disclosed here, is exceeded, the follower or driven magnetic disc falls out of step and stops. The load cannot be picked up again unless the driving member is stopped and the unit restarted. The proper adjustment of magnetic gap is determined by threaded adjustment of eccentric shaft and/or motor shaft. As the gap is increased, the torque is reduced thereby reducing the magnetic pull between the discs. The purpose of changing the gap is primarily for 15 operating the pump at maximum operating capabilities and secondly to provide a much needed safety feature by eliminating the usual safety or relief valve found in ordinary hydraulic systems.

As shown in FIG. 3, the fluid is adapted to be pumped by a 20 fluid displacement pump means. Referring more specifically to FIG. 2 and FIG. 5, the fluid is adapted to enter intake port 61, through intake recess 63 of pump block 33, to the internal inlet port 65 into bore 67 of inlet insert seat 69. Inlet disc 71 is seated on the insert seat 69 to allow fluid to enter at specified 25 times and prevent the fluid to reverse flow at the junction. To adjust the amount of fluid entering, an adjusting screw 73 is threaded into bore 75 to a predetermined distance and then set screw 77 is taper threaded into slotted bore 79 of adjusting screw 73, thereby expanding the head of the adjusting screw 40 73 to hold it in this position after adjustment has been made. A pipe plug 81 is threaded into the bore 83 of the pump block 33 for sealing the access holes after making adjustments of the adjusting screw 73. Thus, it is apparent that the amount of 45 fluid flow can easily be varied by setting the adjusting screw 73.

Referring now to FIG. 2 and FIG. 3, the movement of the 50 fluid is caused by reciprocation of the pump means, which comprises a piston 85 in bore 87 of plunger sleeve 89. Plunger sleeve 89 is in turn slidable in bore 86 of block 33 with a pipe plug 88 threadedly fastened thereto. Each piston 85 is connected for reciprocating movement to a piston drive oscillating ring 91, by means of a pivot pin 93. A clevis bushing 95 surrounds each pivot pin 93. The piston drive oscillating ring 55 is in turn connected to the eccentric cam portion 97 of eccentric shaft 47. An eccentric bushing 99 protects the bearing surface of the eccentric cam portion 97 to minimize wear between it and the oscillating ring 91. As shown in FIG. 3 the eccentric shaft 47 comprises the threaded end 51 adjacent the axial shaft, and an eccentric cam portion 97 between the shoulder abutment 101 and pilot bearing 103. Pilot bearing 105 in pilot bore 107 of block 33 prevents radial thrust of the eccentric shaft 47 when rotated. Any axial movement of the eccentric shaft 47 is retained by the thrust washer 109.

60 As shown in FIG. 2, a pair of piston drive oscillating rings 91 are oscillated in recessed bore 111 of pump block 33 causing pistons 85 to move radially in a reciprocating manner as the eccentric shaft 47 is rotated by magnetic disc 57. This is accomplished by providing the piston drive oscillating ring 91 65 with a segment 115 extending perpendicular to, on one side of the ring 91, and parallel to the bore of the ring 91. The bore surface 116 is to provide the piston return. The segment 115, which provides the piston advance, comprises two segmented portions 114 and 116 separated by a radially extended arced recess 113. A bore 114 extends through both segmented por-

tions 145 and 146, and parallel to the bore of ring 91, for reception of pin 93. Thus, as the eccentric shaft 47 is rotated by the magnetic disc 57, the eccentric cam portion 97 is eccentrically rotated, and the piston drive oscillating ring 91 is caused to be moved radially in an oscillatory motion thereby effecting radial reciprocation of the piston. The arced recess 113 allows oscillatory movement of ring 91 with respect to the pivot pin 93.

On the inlet side of the pump, with the movement of the piston 85 radially inward, a suction is formed causing the disc 71 to move upward against the end of adjusting screw 73, allowing fluid to flow from bore 67, port 65, and recess channel 63 to flow by disc 71 and enter channel 117 to bore 119 of exit insert seat 121. On the exhaust side of the pump, a disc 123 is seated on top of the exit insert seat 121, with an adjusting screw 125 threadedly seated for adjustment of fluid flow therethrough. Set screw 127 is threaded in taper threaded and slotted bore 129 of adjusting screw 125 to hold it in position once the fluid flow adjustment has been made. As on the inlet side of the pump, a pipe plug 131 is threaded into bore 133 of the pump block 33 for sealing the access holes after making adjustments on the adjusting screw 125.

With the movement of piston 85 radially outward, as viewed in FIG. 2, the inlet disc 71 moves against the inlet insert seat 69 and thus prevents fluid flow from entering bore 67, port 65 and recess channel 63; however, the exit disc 123 is pushed open by the pressure of fluid flow and thus allows the fluid to escape into exit channel 135 to exit port 137, and thence out through line 19.

The high efficiency of this unit is attributed to the pumping unit being hermetically sealed from the driving means. Another important feature is that in a corrosive fluid mixture, such as ammonia and others, the bearing parts are able to withstand the corrosive action of the fluid; that is, bushing 43, washer 109, bushing 95, bushing 99, 105, 89 are made of carbon, or other suitable material. It is to be noted that the fluid is

allowed to enter all areas on the driven or pump side of the unit by means of allowing fluid to flow from recess channel 63 through slots 139 and 141 of pump block 33, through holes 143 of pump shaft housing 31, as shown in FIG. 2 and FIG. 5.

It is to be further noted that the capabilities of this hermetically sealed pump unit encompass the use of food substances.

I claim:

1. In a hermetically sealed pump, comprising:

I. a motor means;

A. a first magnetic disc connected to the shaft of said motor means;

II. a pumping means;

A. a second magnetic disc connected to a shaft of said pumping means;

B. piston drive means connected to said eccentric shaft, said piston drive means comprises:

1. a pair of piston drive oscillating rings;

2. each of said piston drive oscillating rings comprises:

a. an annular ring portion, having an axial bore therethrough, to provide for the piston movement;

b. a piston advance segment connected on one side of said annular ring portion extending perpendicular thereto and parallel to the axis of said axial bore;

c. said segment having an arced recess extending outwardly radially from said axial bore and providing two segmented portions;

d. a bore extending through said two segmented portions, adapted to receive a piston pin therethrough;

3. a piston connected to said segmented portions, by means of said piston pin;

C. inlet and outlet flow means; and

III. a nonconducting and nonmagnetic seal interposed between said first and said second magnetic discs.
